DESIGN FOR AN OVERSHOE

Lucille B. Fitzgerald, Naugatuck, Conn., assignor to United States Rubber Products, Inc., New York, N. Y., a corporation of Delaware

Application February 3, 1938, Serial No. 74,824

Term of patent 3½ years

To all whom it may concern:

Be it known that I, Lucille B. Fitzgerald, a citizen of the United States of America, residing at Naugatuck, county of New Haven, State of Connecticut, have invented a new, original, and ornamental Design for an Overshoe, of which the following is a specification, reference being had to the accompanying drawing, forming a part thereof, wherein:—

Fig. 1 is a perspective view of one side of the overshoe; and

Fig. 2 is a similar view of the other side of the overshoe.

I claim:

The ornamental design for an overshoe, as shown.

LUCILLE B. FITZGERALD.
